UNITED STATES PATENT OFFICE

158,030

ENCLOSED CRIB

William A. Wagner, Evergreen Park, Ill., assignor
to Chauncey C. Potter, Arlington, Va.

Application July 8, 1947, Serial No. 140,148

Term of patent 14 years

(Cl. D5—5)

To all whom it may concern:

Be it known that I, William A. Wagner, a citizen of the United States, residing at Evergreen Park, in the State of Illinois, have invented a new, original, and ornamental Design for Enclosed Crib, of which the following is a specification, reference being had to the accompanying drawings, forming part thereof.

In the drawings:

Fig. 1 is a perspective view of an enclosed crib, showing my new design.

Fig. 2 is an end elevational view.

Fig. 3 is a front elevational view.

I claim:

The ornamental design for an enclosed crib, as shown.

WILLIAM A. WAGNER.
